Patented Oct. 24, 1922.

FIG. 1.

FIG. 3.

FIG. 4.

FIG. 5.

George E. Burton
INVENTOR

Joe Babo, Jr.
WITNESS

Victor J. Evans
ATTORNEY

UNITED STATES PATENT OFFICE.

GEORGE E. BURTON, OF PHILADELPHIA, PENNSYLVANIA.

SHARPENER FOR ROTARY CUTTERS.

Application filed August 8, 1921. Serial No. 490,636.

To all whom it may concern:

Be it known that I, GEORGE E. BURTON, a citizen of the United States, residing at Philadelphia, in the county of Philadelphia and State of Pennsylvania, have invented new and useful Improvements in Sharpeners for Rotary Cutters, of which the following is a specification.

This invention relates to device for sharpening rotary cutters and it has more particular reference to a means whereby the cutters of pencil sharpeners of the "Boston," "Dexter" and other well known types of such nature may be reground or be sharpened whenever desired.

Another object of my invention is to provide a novel device which can be promptly positioned on a rotary cutter pencil sharpener by an inexperienced person and the cutters reground or sharpened by simply rotating the machine as when pointing a pencil or the like.

A further object of this invention is to provide a novel sharpening means for rotary cutters which is simple and inexpensive to construct, comprises but few parts which are capable of prompt assembly and adjustment, and that cannot easily get out of order or rendered ineffective.

With the foregoing and other objects in view as will later on become more apparent as this description proceeds my invention consists essentially in the novel construction, combinations and arrangements of parts hereinafter fully described, and more specifically defined by the appended claims.

In the further disclosure of the invention reference is to be had to the accompanying sheet of explanatory drawings constituting a part of this specification and in which like characters of reference designate the same or corresponding parts in all the views.

Figure 1 is a side view of a pencil sharpener of the "Boston" type having the cover removed and with my cutter grinder in applied position thereon.

Figure 2 is a front end elevation of the grinder attachment as applied.

Figure 3 is an enlarged perspective view of the grinder attachment main frame.

Figure 4 is an enlarged perspective view of one of the grinder holders or shoes; and

Figure 5 is an enlarged perspective view

of one of the spring influenced gripping jaws or members hereinafter particularly described, part being broken away for a clearer understanding of the underlying structure.

Referring more particularly to the views the numeral 6 designates the standard of an ordinary "Boston" or similar pencil sharpener fitted with the customary rotary cutters 7 adapted for rotation through appropriate gearing by a crank handle 8 and 9 indicates the usual tubular boss or pencil supporting holder in which the pencil is disposed during the operation of pointing, all of said parts being in accordance with the well known patterns and arrangements and being only briefly referred to for a better understanding of my invention.

According to my invention I form the main frame 10 Figure 3 from a sheet metal blank of suitable gauge or thickness which is subsequently tempered to the requisite degree, said frame 10 being fashioned with a central aperture 11 of a diameter to pass easily over the aforesaid tubular boss 9 and cut out or spaced laterally-turned substantially S-shaped spring arms 12, the free ends whereof are coiled or turned over to constitute journals or hinge supports 13 for transversely disposed wires or rods 14. The said frame 10 is also provided with diagonally opposed outstanding projections or ears 15 for abutment against the cutter holder frame of the standard 6 and as clearly shown in Figure 1 and diametrically opposed lips or upset members 16 appropriately stamped out therefrom, and in addition thereto are diagonally aligned longitudinal parallel slots 17 and pin holes 18 the purpose whereof will be more fully explained. Mounted on the above referred to wires or rods 14 are holders or equalizer members 19 suitably made from sheet metal blanks and fashioned to provide a medial pivotal portion 20 and turned over ears or gripping members 21 between which the abrasive or other suitable material blocks 22 are securely clamped and supported in opposed relation as will be clearly understood by those acquainted with the art to

which this invention appertains. It will of course be readily recognized that the blocks 22 when secured in the equalizers or holders

19 are hingedly suspended in opposed relation on the wires or rods 14 by means of the rolled or channeled medial parts 20; or said parts 20 may be secured to the rods or 5 wires 14 and the latter be hingedly mounted or journaled in the coiled or turned over hinge supports 13.

Slidably mounted on the outer face of the aforesaid main frame 10 are opposed spring 10 influenced jaws 23 each of which is fashioned from a sheet-metal blank to provide a finger hold 24 at one end and a V-shaped cut-out 25 at the opposed end flanked by outwardly turned flanges or parts 26, chamfered or tapered down at 27 to terminate in or provide a notched end 28 for the purpose later on explained. Stamped out from each jaw 23 are spaced parallel tongues 29 which are passed through the aforesaid diagonal 15 slots 17 the ends 30 being thereafter laterally turned whereby said jaws 23 are slidably mounted on the frame 10 in opposed relation and adapted for movement towards or away from each other as will be clearly 20 apparent to those acquainted with the art and on an examination of the drawings. In order that the jaws 23 may be normally influenced towards each other I preferably employ the means shown and which consists of a tempered steel recoil wire or spring 25 31, the free end whereof seats against the aforementioned notched end 28 of the outwardly turned flanges or parts 26, whilst the other end 32 is passed through the adjoining pin hole 18 and an intermediate part is 30 passed under the aligning lip or upset latch member 16 whereby it will be clearly seen from Figure 2 that the said jaws 23 are spring influenced towards each other and 35 forced into gripping engagement on the tubular boss 9. It is also to be remarked that the abrasive blocks 22 are made of a length to accommodate any length of ordinary rotary cutter 7 and wide enough to 40 permit of a large surface for operating on said cutters, whilst one or both ends 33 thereof may be beveled to allow close approach to the head of the standard 6 and thereby grind the full length of the said 45 cutters. Obviously the hinging of the abrasive or other blocks 22 as set forth provides for their automatic adaptation to 50 differently coned or angularly inclined cutters 7.

55 In use and assuming that the chip cover or casing has been removed from the head of the standard 6, the jaws 23 are separated by expansive pressure exerted on the finger holds 24 whereupon the device is slipped 55 into position as shown by Figure 1, that is to say, with the abrasive blocks 22 longitudinally of the rotary cutters 7 and their beveled ends 33 in close juxtaposition or near contact with the head of said standard 6.

60 65 On turning the crank handle 8 in a clock-

wise direction or to the right-hand it will be self-evident that the rotary cutters 7 will be completely ground or resharpened over their entire length by a simple operation analogous to the ordinary operation of 70 pointing a lead pencil, crayon or the like.

From the foregoing description it will be clearly apparent that by my invention I have provided an extremely simple and very effective device for the purpose specified; 75 and whilst there has been shown and fully described one practical embodiment thereof the same is not to be deemed as restricted thereto; as the invention is susceptible of easy adaptation for other uses than the precise form described, and the right is hereby reserved to make such changes, variations and other adaptations thereof as fairly lie within the scope of the appended claims.

Having described my invention what I 85 claim as new and desire to secure by Letter Patent is:

1. A sharpening device for rotary cutters comprising a frame, flexibly and hingedly mounted opposed abrading means 90 carried by said frame, and means for supporting said frame and abrading means in operative position on the rotary cutters to be sharpened.

2. A sharpening device for rotary cutters 95 comprising a frame, flexibly and hingedly mounted opposed abrading means carried by said frame, and opposed spring influenced jaws for supporting said frame and abrading means in operative position on 100 the rotary cutters to be sharpened.

3. A sharpening device for rotary cutters comprising a frame having pairs of laterally projecting spaced flexible arms the ends whereof are fashioned to provide hinge 105 bearings, abrading means hingedly mounted in opposed relation between the pairs of spaced flexible arms, and spring influenced means for supporting said frame and abrading means in operative position on the 110 rotary cutters to be sharpened.

4. A sharpening device for rotary cutters comprising a plate frame having a central aperture therein and pairs of laterally projecting S-shaped spring arms the free 115 ends whereof are fashioned to provide hinge bearings, longitudinal abrading members pivotally mounted in the hinge bearings between the pairs of spaced spring arms, and spring influenced means for supporting said 120 frame and abrading members in stationary position on the rotary cutters to be sharpened.

5. A sharpening device for rotary cutters comprising a plate frame having a central aperture therein and pairs of laterally projecting S-shaped spring arms the free 125 ends whereof are fashioned to provide hinge bearings, opposed longitudinal abrading blocks supported by gripping members and 130

a transverse hinge pin between the pairs of spaced spring arms, and spring influenced means for supporting said frame and abrading blocks in stationary position on the 5 rotary cutters to be sharpened.

6. A sharpening device for rotary cutters comprising a plate frame having a central aperture therein, laterally extending diagonally opposed ears on one side and 10 pairs of projecting S-shaped spring arms the free ends whereof are fashioned to provide hinge bearings, opposed longitudinal abrading blocks supported by gripping members and a transverse hinge pin between 15 the pairs of spaced spring arms, and spring influenced jaws slidable on the aforesaid frame for automatically centering the device in stationary position on the rotary cutters to be sharpened.

20 7. A sharpening device for rotary cutters comprising a plate frame having a central aperture therein, laterally extending diagonally opposed ears on one side and pairs of projecting S-shaped spring arms the free 25 ends whereof are fashioned to provide hinge bearings, opposed longitudinal abrading blocks supported by gripping members and a transverse hinge pin between the pairs of spaced spring arms, manually expandible 30 opposed jaws slidable on the face of the aforesaid frame, and means normally tending to force said jaws towards the centre of the aforesaid central aperture.

8. In a sharpening device for rotary cutters including abrading means and means for supporting said device relative to the cutters to be sharpened, the combination of a main or plate frame having a central aperture therein, laterally projecting diagonally opposed ears and integral pairs of opposed S-shaped spring arms on said plate-frame the free ends

whereof are fashioned to provide hinge bearings for the abrading means.

9. In a sharpening device for rotary cutters including a main frame and opposed spring influenced jaws for supporting said frame relative to the cutters to be sharpened, the combination of opposed resiliently and hingedly mounted abrasive holders, each 45 50 of said holders comprising a plate member having a medial transverse hinge portion and fold-over ears for gripping the abrasive material.

10. In a sharpening device for rotary cutters including a main frame having slots and resiliently mounted abrasive holders hingedly supported by the frame, the combination therewith of jaws for positioning and automatically centering the device on the cutters to be sharpened, said jaws having forked 55 60 inner ends flanked by outset flanges and opposed finger holds, spaced tongues on said jaws adapted for passage through the slots in the main frame whereby they are slidably 65 mounted thereon, and recoil means for normally forcing said jaws towards each other.

11. In a sharpening device for rotary cutters including abrading means and spring influenced means for supporting said 70 device relative to the cutters to be sharpened, the combination of a main or plate-frame having a central aperture therein, laterally projecting diagonally opposed ears outstanding therefrom, integral pairs of opposed 75 S-shaped spring arms laterally outstanding on the same side as the opposed ears and having their free ends fashioned to provide hinge bearings, and outset lips on the opposite face of the plate frame serving as 80 tension members for the aforesaid spring influenced supporting means.

In testimony whereof I affix my signature.
GEORGE E. BURTON.
